UNITED STATES PATENT OFFICE.

HARRY F. GARDNER, OF BATTLE CREEK, MICHIGAN, ASSIGNOR TO CEMENT
PRODUCTS COMPANY, OF BATTLE CREEK, MICHIGAN.

DESIGN FOR A COUCH-CASKET.

45,930.

Specification for Design.

Patented June 16, 1914.

Application filed April 18, 1914. Serial No. 832,981. Term of patent 3½ years.

To all whom it may concern:

Be it known that I, HARRY F. GARDNER, a citizen of the United States, residing at Battle Creek, county of Calhoun, State of Michigan, have invented a new, original, and ornamental Design for Couch-Caskets, of which the following is a specification, reference being had to the accompanying drawing, forming a part thereof.

The figure is a front perspective view of a couch casket showing my new design.

I claim:

The ornamental design for a couch casket, as shown.

HARRY F. GARDNER.
